UNITED STATES PATENT OFFICE.

JOHN WOOD ENRIGHT, OF NEW ORLEANS, LOUISIANA.

RAIL-ANCHOR.

1,050,725.

Specification of Letters Patent. Patented Jan. 14, 1913.

Application filed April 26, 1912. Serial No. 693,287.

To all whom it may concern:

Be it known that I, JOHN W. ENRIGHT, a citizen of the United States, and a resident of New Orleans, in the parish of Orleans and State of Louisiana, have invented a new and Improved Rail-Anchor, of which the following is a full, clear, and exact description.

This invention relates to means for securing railway rails in place, and has particular reference to devices for securing rails from creeping and lateral displacement.

The invention consists of the peculiar and novel details of construction hereinafter fully described and claimed and illustrated in the accompanying drawings, in the several figures of which corresponding parts are referred to by similar reference characters, and in which—

20. Figure 1 is a perspective view of a rail clamped to a tie by one form of this device; Fig. 2 is a plan view of the same, the tie being omitted; Fig. 3 is a transverse section substantially on the line 3—3 of Fig. 2; Fig. 4 is a side elevation of a modified form of the invention; and Fig. 5 is a transverse section of the same on the line 5—5 of Fig. 4.

That form of the invention first referred to comprises a substantially flat base plate 10 adapted to rest upon a cross-tie 11 to which it is adapted to be secured by spikes 12 passing through holes 13 and into the cross-tie. The plate 10 has secured thereto, or preferably formed integral therewith, a pair of flanges 14 and 15 which extend upward and toward each other, forming recesses 14^a and 15^a which receive the lateral edges of the base flange 16 of the rail R.

40. When the base flange 16 is seated in place, one of its edges will be received snugly within the space 14^a and its opposite edge will be spaced laterally from the flange 15 by a distance equal to or slightly greater than the extent of inward projection of the flange 14, so that in assembling the rail and anchor one edge of the base flange on being slipped wholly within the space 15^a, the opposite edge may freely pass the flange 14, and subsequently the rail may be moved laterally with the base flange into its final position, as indicated by dotted lines in Fig. 5. Not only is the flange 15 spaced laterally from the adjacent edge of the base of the rail, but also it is spaced vertically, the inwardly projecting portion of the flange

overlapping the adjacent edge of the rail base. The said flange 15 furthermore is spaced from the rail base more at one end than at the other; in other words, the space is wedge shaped, and into such space is driven a wedge 17 adapted to snugly fill both the lateral and vertical spaces above mentioned between the rail base and the vertical overlapping portions, respectively, of the flange 15. By reason of the fact that the inwardly projecting part of the flange 15 overlaps the adjacent edge of the base 60 of the rail, the action of the wedge 17 on operating directly between said base edge and the overlapping portion of the flange 15 will positively clamp the base plate 10 of the chair against the bottom of said rail base. This result of the wedging action is increased in practice by forming the wedge 65 so that a slight space is left between the plate 10 and the lowermost portion of the wedge; that is to say, the vertical thickness of the wedge adjacent the vertical portion of the flange 15 is made in practice slightly 70 less than the space into which this portion of the wedge is adapted to operate. The wedge, however, snugly filling the space directly between the overlapping portion 75 of the flange and the adjacent edge of the base of the rail insures that the rail base and the chair plate will be firmly clamped together even though the rail base may become slightly thinner by usage. The wedge 80 is substantially straight though tapered throughout its length, but is formed along an upper edge with one or more notches 17^a into which, after the wedge is driven home, a part or parts of the thin edge 15^b of the flange 15 may be swaged by any suitable 85 tool. This expedient insures that the wedge cannot inadvertently become displaced and hence the rail and anchor plate must maintain the relative position in which they are placed. The wedge 17, however, is provided with a head 17^b whereby it may be driven out when it becomes necessary to detach the anchor from the rail. 90

That form of the invention shown in Figs. 4 and 5 is substantially identical with that above described with respect to the anchor plate, upwardly and inwardly extending flanges, and the wedge features. Instead, however, of this anchor being secured as by spikes to the top of the cross-tie, it is provided with a downwardly projecting arm or brace 18 adapted to bear against the side 100 105 110

of the cross-tie or to be engaged with any other stationary abutment, depending upon the length and form of said brace 18.

The anchor constituting the subject of this invention may be made of any suitable material and the parts thereof may be variously constructed with respect to relative sizes and proportions without departing from the spirit of the invention herein-
10 after claimed.

Having thus described my invention, what I claim as new and desire to secure by Letters Patent is:

1. The herein described rail anchor comprising a plate to receive a rail, said plate having a pair of flanges to embrace the opposite edges of the rail base, one of the flanges receiving its base edge snugly and the other flange being spaced from the adjacent base edge both laterally and vertically, and a wedge driven between the latter flange and the rail base and snugly fitted into both the lateral and vertical spaces specified said wedge being formed with a depression
20 on an outer edge and a portion of the co-
operating flange being swaged thereinto, for
25 the purpose set forth.

2. The herein described rail anchor comprising a base plate having a pair of opposite integral flanges extending upwardly 30 therefrom and thence inwardly toward each other to embrace the base flange of a rail, one of said flanges receiving one edge of the said rail base snugly, and the other of said flanges being spaced from the other 35 rail flange edge, both laterally and vertically, said space being tapered both laterally and vertically, a smooth wedge driven snugly within said space, means being provided to cause the said wedge to be interlocked with its coöperating anchor flange, the wedge having a head whereby it may be driven out of interlocking position, and an integral brace arm extending downwardly 40 from the anchor base and into lateral co-
operation with some fixed abutment, sub-
stantially as and for the purpose set forth.

In testimony whereof I have signed my name to this specification in the presence of two subscribing witnesses.

JOHN WOOD ENRIGHT.
